UNITED STATES PATENT OFFICE.

GEORGE W. DOVER, OF LONGMEADOW, RHODE ISLAND, ASSIGNOR TO JUSTIN HENDERSON, OF LARCHMONT, NEW YORK.

ORNAMENTAL MOUNTING AND METHOD OF MAKING THE SAME.

Application filed March 20, 1925. Serial No. 17,008.

This invention relates to an ornamental mounting and method of making the same which is adapted for use in the production of jewelry articles, such as pendants, necklaces, brooches, earrings, pins, bracelets, buckles, rings, dress ornaments, etc.

One object of the invention is to provide an ornamental mounting of pleasing appearance and unique design so constructed 10 as to give the appearance of being formed of a metallic fabric material which may serve as a background for a suitable gem setting or other ornament.

Another object of the invention is to provide an ornamental mounting formed from metallic fabric material, so arranged and supported as to give the appearance of being formed entirely of fabric throughout, the said fabric material being adapted to 20 receive a deposit of precious metal of a desired color thereby simulating the appearance of certain ornamental woven fabrics.

Other objects and advantages of the invention relate to certain combinations of 25 steps and methods of operation adapted to facilitate the construction of the ornamental mounting and enhance the artistic appearance of the completed article.

In the accompanying drawings forming 30 a part of the description of the invention:—

Fig. 1 is a plan view of the basic material from which the mounting is formed, the parts being arranged in the position which they occupy at the first part of the shaping 35 operation.

Fig. 2 is an enlarged vertical sectional view taken along the line 2—2 of Fig. 1.

Fig. 3 is a plan view of the material shown in Fig. 1, the edge portions thereof 40 being upturned as in a further step of the shaping operation.

Fig. 4 is a plan view of the material shown in Fig. 1, the edges of the material 45 being inturned and folded over towards the center.

Fig. 5 is a plan view of the structure similar to that shown in Fig. 4, but showing the provision of a seat for the gem setting and an opening formed at the center thereof and 50 in the rear of the position to be occupied by the gem.

Fig. 6 is a plan view of the completed mounting, and,

Fig. 7 is an enlarged vertical sectional view of the same, taken along the line 7—7 of Fig. 6.

In the form of the invention illustrated herein, 1 designates a plate of thin flexible metal which serves as a base for the ornamental mounting and imparts thereto a sufficient degree of rigidity to insure that it will retain its shape under ordinary conditions of use, 2 is a relatively coarse mesh metallic fabric which is positioned next to the metal base 1, and 3 designates a relatively fine mesh metallic fabric which is placed over the coarse fabric 2 and farthest from the metal base.

In the formation of the ornamental mounting as above described, it is an important feature of the invention that metallic fabric 2 be interposed between the metal base 1 and the metallic fabric 3. If the metallic fabric 3 is placed upon the metal base 1 without the interposition of a separate fabric 2 therebetween, the light will strike through the interstices in the metallic fabric 3 to the metal base 1 and be reflected therefrom thereby disclosing the presence of a metallic base plate and destroying the desired and pleasing effect of depth which is obtained by interposing a layer of fabric between the metal base and the outer fabric 3. The layer of metallic fabric 2 also serves to give greater rigidity to the completed structure and thus insure that the fabric folds 6, formed in bending the fabric will retain the shape and form imparted to them under the usual conditions of use. While the fabric 2 employed may be of the same mesh as the fabric 3, I prefer to employ a fabric of somewhat coarser mesh next to the metallic base, such, for example, as 80 mesh to the inch, while I prefer to employ a finer mesh, such, for example, as 100 mesh to the inch, as the outer fabric layer which is designated by the numeral 3 in the drawings.

I preferably form the metal base 1 and fabric 2 of approximately the same size, and the fabric sheet 3 slightly larger than metal base plate 1 so that a margin 4 of the fabric 3 extends outwardly and may be bent over the edge of the metal base 1 to hold the parts together, as indicated at 5.

When the marginal portion 4 has been

bent over the metal base 1 entirely there-around, the three layers are held together by the inturned edge folded against the metal plate as at 5 and may be manipulated 5 together as a unit.

The composite sheet material thus formed is then bent upwardly at its edge, preferably about a central former (not shown) each side of the octagonal shaped sheet being bent 10 upwardly as a unit whereupon the material assumes the form shown in Fig. 3 of the drawings, the portions at the corners of the octagonal blank forming folds as indicated at 6, and the remaining portions forming 15 upstanding portions 7 between the folds 6. The central former about which the edges of the composite sheet are bent may be round, oval, or any other desired contour, depending upon the shape of mounting desired, but in the present instance the former is of oval shape as will be seen upon reference to Fig. 3.

The up-turned edges 7 of the composite material shown in Fig. 3 are then bent inwardly and downwardly against the inner surface of the metal base plate 1, the folds 6 being curved as desired to add to the ornamental appearance of the mounting whereupon the mounting assumes the appearance 30 shown in Fig. 4 of the drawings.

At this stage in the construction of the mounting, a seat 8 may be formed upon the infolded ends of the composite material for the reception of a gem setting, the seat being 35 formed by pressing a suitable die thereon or in any other desired manner. An opening 9 is also preferably formed in the center of the composite sheet and directly behind the seat for the gem setting for the purpose of 40 admitting light at the rear of the gem.

At this time, one or more supports may be secured to the ornamental mounting by means of which the same may be secured to a necklace, earring or other device to which the same is to be attached. As one form of 45 support which is found to be adapted for this purpose, I have shown an eye-pin 10 provided with a slender shank 11 and having a collar 12 cooperating therewith.

The insertion of the eye-pin 10 in the ornament is effected by first forming a small opening through the fabric and base plate with a suitable piercing tool, the opening being sufficiently small to barely admit the 50 shank 11 of the eye-pin. The collar 12 is then placed over the shank 11 and the shank forced into the opening formed in the material where it is held largely by friction but may be firmly secured by melting a 55 drop of solder in such position that the same will flow around the shank 11 and firmly secure it to the fabric 3 and base plate 1.

It will be seen upon reference to Fig. 6 60 of the drawings that the inturned fabric material is formed to provide radial folds 15

throughout the greater extent of the in-turned edge portion, and that ornamental folds or whorls 16 are formed adjacent to the ends of the oval ornament. While this arrangement of the folds is shown as illustrating one method of forming the fabric to produce a pleasing and artistic effect, it is to be understood that the invention is in no way to be regarded as limited to the particular arrangement or form of fold as 70 shown herein since I am aware that the fabric may be shaped and arranged in various ways and with various forms and combinations of pleats and folds to give the same an ornamental and pleasing appearance to the eye. A gem setting 17, provided with an upwardly extending rim 18 for overlying the edge of an ornamental stone 19, is placed upon the seat 8 formed as previously described and firmly secured thereto 75 by soldering or by any other suitable means. A back plate 20 having a central opening therein of similar contour to the opening 9 and provided with an inturned edge 21 surrounding said central opening is secured to 80 the back of the ornamental mounting by soldering or otherwise. The back plate 20 is secured to the back of the ornamental mounting in such a manner that the in-turned edge 21 projects within the central 85 opening 9 to partially or wholly conceal 90 from view the raw edges of the inturned fabric.

The metallic fabric 3 may be formed of a precious metal as gold or silver or may be 95 made up of a suitable base metal and a plating of gold or silver applied thereto at a suitable point in the manufacture of the mounting.

From the above description, taken in connection with the accompanying drawings, it will be seen that I have provided a novel method of forming an ornament which is of pleasing and artistic appearance and which is capable of use for a variety of different 105 purposes in connection with jewelry and allied arts. While I have set forth with considerable particularity the exact construction of one form of the ornament and the 110 particular steps and sequence of steps which 115 may be employed in its construction, it is to be understood that the ornament is capable of considerable modification in form, shape and arrangement of ornamental features as 120 well as in the various steps and sequence of steps employed in its formation, and I therefore do not desire to be limited to the exact construction shown and described nor to the use of the exact steps and sequence of steps 125 employed, except as the same may be included within the terms of the following claims when broadly construed in the light of my invention.

What I claim is:

1. A mounting for jewelry formed from 130

a sheet of composite material the edges of which are folded inwardly therearound to serve as a background for an ornament, the said composite sheet being made up of a 5 plate of bendable metal, a layer of metallic fabric, and a second layer of fabric material interposed between said plate and said first named metallic fabric, the edges of said composite sheet being folded to expose to 10 view the layer of metallic fabric and conceal the plate of bendable metal.

2. A mounting for jewelry comprising a plate of bendable metal, a layer of metallic fabric positioned upon one face of said 15 plate, and a second layer of fabric material interposed between said plate and said first named metallic fabric, the edges of said plate and fabric layers being folded inwardly upon the metal plate to form upon one face 20 of said mounting a plurality of radially extending folds of metallic fabric.

3. An article of jewelry comprising a mounting formed from a sheet of composite material including a plate of bendable metal 25 and layers of metallic fabric positioned upon one face of said plate, the edges of said composite sheet being folded inwardly upon said metal plate to conceal the metal plate from view; and an ornament seated upon 30 and firmly secured to the inturned edges of the outer layer of metallic fabric.

4. An article of jewelry comprising a mounting formed from a sheet of composite material including a plate of bendable metal and layers of metallic fabric positioned upon one face of said plate, the edges of said composite sheet being folded inwardly upon said metal plate to conceal the metal plate from view, said mounting 35 being provided with a central opening, and a gem secured to the inturned edges of the outer layer of metallic fabric and overlying the opening in said mounting.

5. An article of jewelry comprising a mounting formed from metallic fabric material overlying a metal plate and having the edges thereof inturned to provide a seat 45 for an ornament, said mounting being provided with a central opening, a back plate 50 secured to said mounting and surrounding the opening therein, and an ornament se-

cured to said seat in front of the opening formed in the mounting.

6. An article of jewelry comprising a mounting formed from a metal plate and 55 metallic fabric material overlying said plate and having its edges inturned thereover to provide a seat for an ornament, an ornament secured to said seat, and a support for said mounting comprising a member provided 60 with a shank adapted to be inserted in said fabric and plate, and means for securing said shank against removal therefrom.

7. The method of making a mounting for jewelry which comprises, positioning a 65 layer of metallic fabric upon one face of a plate of bendable metal, the metallic fabric being of slightly greater extent than the plate, bending the edges of said fabric over the edges of said metal, and then bending 70 said metal and fabric inwardly throughout the entire periphery thereof whereby the metallic fabric completely overlies a substantial portion of the metal plate.

8. The method of making a mounting for 75 jewelry which comprises, positioning a layer of metallic fabric upon one face of a plate of bendable metal, the metallic fabric being of slightly greater extent than the plate, bending the edges of said fabric over the 80 edges of said metal, bending said metal and fabric inwardly throughout the entire periphery thereof, perforating the metal fabric and plate to form an opening substantially centrally thereof, and securing an ornamental stone to the inwardly extending edges of said fabric whereby said ornamental stone will be firmly secured thereto opposite the central opening in said plate and 85 fabric.

9. The method of making a mounting for 90 jewelry which comprises, placing a sheet of metallic fabric upon one side of a plate of bendable metal, bending the edges of said metal and fabric inwardly upon the said metal whereby the metallic fabric completely overlies a substantial portion of the metal plate.

In testimony whereof I have affixed my signature.

GEORGE W. DOVER.
